UNITED STATES PATENT OFFICE

ELIE W. LABOMBARDE, OF NASHUA, NEW HAMPSHIRE

TUBULAR BOX

Application filed August 18, 1929. Serial No. 386,752.

This invention relates to paper boxes or containers and has particular reference to such articles in tubular form and preferably hexagonal in cross section for reasons herein-
5 after explained.

The object of the present invention is to provide strong, durable, and economically produced containers capable of holding liquids such as milk, or dry food material 10 which is usually sold in tin containers, such as coffee, and which therefore must be moisture-proof and air-tight.

With said object in view, the invention consists in the structure of the containers 15 and the blanks from which they are made, substantially as hereinafter described and claimed.

Of the accompanying drawings:—

Figure 1 is a plan view of the blank in its 20 first condition prior to any folding, the mid-portion of the blank being illustrated as broken out, to indicate that it may be of any width according to the capacity which the container is to have.

Figure 2 represents a section on line 2—2 of Figure 1.

Figure 3 is a view similar to Figure 1 but illustrating the blank in its second condition.

Figure 4 represents a section on line 4—4 of Figure 3.

Figure 5 is a top plan view of the completed box.

Figure 6 represents a section on line 6—6 of Figure 5, on a larger scale.

Figure 7 is a perspective view of the container made up from one of the blanks as illustrated.

Similar reference characters designate 40 similar parts or features in all of the views.

Referring to Figures 1 and 2, the blank is 45 died out and creased to form body panels 12, each having a tapering lip 13, the latter being transversely grooved as at 14 in a straight line from one end of the body strip to the other. The sheet from which the blanks are died out preferably consists of two or more plies, treated to render the material moisture-proof, or the moisture-proofing treatment 50 may be deferred until the boxes are com-

pleted and then effected by immersing the boxes in paraffine and then draining them.

The creases which define the panels 12 of the strip are indicated at *x*, said creases being parallel and in line with the recesses or notches which separate the lips 13. Extending lengthwise of the strip are two creases *y y* which are to define the lines on which the lips 13 are to be folded as presently described. At one end of the strip is a projecting flap 15 the ends of which are in line with the creases *y y*.

After the blanks have been cut out and grooved and creased as so far described, they may be stored until they are to be converted 55 to the condition illustrated by Figures 3 and 4, or to final receptacle condition.

To convert them to the condition illustrated by Figures 3 and 4, stripes of glue 16 (Fig. 1) are first applied lengthwise of the strip, between 60 the creases *y y* and the inner ends of the notches which separate the lips 13 from each other, and then the marginal portions of the strip are folded in on the lines *y y*, pressure being exerted on the blank during such fold-

ing as will collapse the grooved areas 14 into well-defined shoulders or ledges 17 (Figs. 3 and 4), said ledges being along a line intermediate the length of the folded-back portions of the blank. Such pressure tends to 65 diffuse or spread the glue stripes so as to retain the lips and ledges firmly in their folded condition.

In this condition the blanks may be stored or immediately converted to final receptacle condition as will now be described. 70

By rolling the blank of Figure 3 to substantially cylindrical form and overlapping the flap 15 at one end onto the outside of the panel 12 at the other end, and adhesively securing the overlapping parts, the article is in 75 condition to have the bottom disk 18 inserted to position.

Such disk is, of course, of the same shape as the interior of the container. As illustrated, it is octagonal because the body of the container has eight panels. I do 80 not limit myself however to such specific shape. If the blank has but six panels, then the container will be hexagonal in cross section.

Before the bottom disk 18 is inserted in 100

the polygonal tube, glue may be applied to its edge or to the top of the bottom ledge 17. Then said disk is firmly seated on said bottom ledge and not only serves as the bottom closure for the container but also holds the tube open in true polygonal shape. For some uses it is preferable to then coat the interior with paraffine or other suitable moisture repellent material.

16 To close the top of the receptacle after it has been filled, I employ a disk 19 of the same shape as the disk 18, said disk 19 preferably having a sufficient amplitude of wax coating so that when it is pressed down and seated on 15 the upper ledge 17, such wax will effectively seal the receptacle. Or there may be sufficient wax on the upper ledge to result in effective sealing when the disk is seated on it.

As illustrated in Figures 5 and 6, the upper disk 19 has a slightly curved cut 20 which, in practice, is so filled with wax that none of the contents of the receptacle can escape therethrough. When the receptacle is to be opened however, any small implement can 25 be pushed through the curved slit and then employed to lift the disk from its supporting ledge and break the edge seal thereof, and remove it.

Reference has been made to making the containers hexagonal in cross section, instead of octagonal as illustrated. An advantage resulting from making them hexagonal is that when a number of them are stored or shipped side by side, they will have flat sides 35 bearing against each other, with no waste spaces between, and serving therefore to mutually sustain each other against outward bulging of the walls when the containers are filled. However, whether the containers are 40 hexagonal or octagonal, the sides are less likely to yield to internal pressure than if made rectangular or circular and of paper no thicker than I find sufficient for the form illustrated and described herein. This is because the panels, although flat, are not wide enough to permit ready bulging between their marginal crease lines.

The reason for indenting the paper material to form the grooves 14 (Figs. 1 and 2) 50 is that such straight grooving not only partially breaks the material so that when the lips are folded over as described it is comparatively easy to collapse such grooved portions to the ledge formation illustrated by 55 Figures 3, 4 and 6, but it also renders it certain that the completed ledges will be in straight continuous lines entirely around the interior of the containers.

Referring to Figure 1, it will be seen that 60 the notches between the lips 13 extend into, or intersect, the grooved portions 14. The result of this is that when the blank is converted to the condition illustrated by Figure 2, there are converging spaces between the 65 individual sections of the ledges, which

spaces are closed up when the blank is folded to complete receptacle form as illustrated by Figure 6 and by dotted lines in Figure 5. Therefore there is no opportunity for liquid contents of the container to escape between any crevices in the ledges.

Having now described my invention, I claim:

1. A blank for the body of a paper receptacle, said blank having parallel crease lines 75 and formed with integral marginal portions folded back and secured between said creases, the said integral folded-back portions being creased to provide ledges in line with each other at an intermediate point of the lengths 80 of said folded-back portions.

2. A blank for the body of a paper receptacle, said blank being transversely creased to form a plurality of panels, each panel section having a backwardly folded tapering 85 lip at each end, and all of the lips at each end of the panels being creased to provide ledges in line with each other at an intermediate point of the lengths of said folded-back portions.

3. A paper container having a tubular body provided with inturned lips at its ends, said inturned lips being creased to provide ledges in line with each other at an intermediate point of the lengths thereof, and closures 95 engaging said lips.

4. A paper container having a tubular body provided with inturned lips at its ends, said inturned lips being creased to provide ledges in line with each other at an intermediate 100 point of the lengths thereof, the said ledges being in close abutting relationship to prevent the passage of air or moisture between them.

5. A paper container of uniform diameter 105 having a multiplicity of flat sides each of which has in-turned lips at its ends, said lips being creased to provide ledges in line with each other at an intermediate point of the lengths of said lips, a disk permanently 110 mounted on the ledges at one end of the container, and a closure removably connected to the other end of the container.

In testimony whereof I have affixed my signature.

ELIE W. LABOMBARDE.
